UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed April 14, 1920. Serial No. 373,788.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to the line-spacing mechanism of revoluble platen typewriting machines, and its object is to eliminate the slipping of the work-sheet upon the platen at the line-spacing operation.

The rotation of the platen does not require as much energy as does the return of the carriage and the operator, anticipating the return of the carriage rather than the rotation of the platen, operates the carriage-returning finger-piece with considerable force, and this shock is transmitted to the platen with a jerk, which results in the platen starting to revolve too quickly to insure the advancement of the work-sheets in unison with each other and the platen.

According to the present invention, the line-space handle is pivoted to drive to the left instead of to the right. A finger-piece at the left-hand end of the carriage receives the shock of the hand in returning the carriage toward the right. This carriage-returning finger-piece may be engaged by the first finger, and the operator may then reach to the line-space handle and operate it toward the left with the thumb, with reduced liability of giving the platen sharp rotative movements.

The operator, when moving the hand leftward, may, however, operate the finger-piece and handle with sufficient force to cause a slight creep or slip of the work-sheet. To overcome this, the handle may be normally locked and the finger-piece may be slidably mounted on the carriage, to release the handle before it can be operated to line-space the platen.

Other features and advantages will hereinafter appear.

In the accompanying drawings,

Figure 1 is a perspective view of the carriage of an Underwood typewriter, showing my invention applied thereto.

Figure 2 is a top plan view of the parts shown in Figure 1, and shows the locking

means which may be used with the line-space lever.

Figure 3 is a showing of the parts in Figure 2 in operated positions.

Figure 4 is a front view of the parts shown in Figure 2.

Figure 5 is a view similar to Figure 2, but shows a rearrangement of the parts, so that the line-space lever may be engaged by the forefinger of the operator, while the lock-release may be engaged by the thumb.

The invention may be used in connection with an Underwood typewriting machine in which the usual platen 1 is fixed on an axle 2 journaled in the ends of a platen-frame 3, which is carried on the carriage 4. A ratchet or line-space wheel 5, having a collar 6, is fixed on the axle, and is rotated by a pawl 7, pivoted on a plunger 8, operated by the line-space lever 9. The line-space lever has a handle or finger-piece 10, and is pivoted to the carriage 4 by a stud 13, which passes through a hub 11. The hub 11 has an arm 12 to engage a bent portion 14 on the plunger 8. A pin 15, extending from the under side of the frame 3, holds one end of a spring 16, the other end of said spring engaging a pin 17, which projects from one end of the plunger 8. This spring urges said plunger forwardly against the arm 12, and the latter throws said lever rightward against an abutment 18 on the front bar 20 of the carriage. A second abutment 19 is formed on the extreme left of said front bar, and a top plate 21 is fixed at both ends by means of screws 22, to both abutments, and, extending between said abutments, forms an opening 23, in which the line-space lever 9 can play. An upwardly-projecting finger-piece 24 is formed on the left end of the fixed top plate 21, to be engaged by the first finger of the left-hand, for returning the carriage. This finger-piece serves as an opposing member when the handle 10 of the line-space lever is engaged by the thumb to draw said handle towards the finger-piece for line-spacing, the finger-piece 24 taking the impact of the hand. The line-space wheel 5 has the usual spring-pressed detent 27. It will be seen that the line-spacing operation will normally take place after the return operation of the carriage has been started, and

that comparatively little force will be employed, so that the platen will not start too suddenly.

In Figure 2 is illustrated means to lock the line-space handle to prevent too sudden a start if the operator should move the hand rapidly leftward. One end of a base plate 25 is fastened to the right-hand abutment 18 by a screw 28. The left end of the base plate 10 is held by a shoulder screw 29 threaded into the abutment 19. A locking lever 26 is pivoted on a screw 33 on the plate 25, and extends over the line-space lever 9 when said lever is in its extreme rightward position. A top plate 31 rests on the base plate 25, and has sliding relation therewith, said sliding being limited by the slots 32, which engage the screws 28 and 29. The movable top plate 31 is normally held in an extreme leftward position by a spring 34, which extends between the projection 35 on the top plate and a similar projection 36 on, and near one end of, the base plate 25.

A pin 37 in the top plate 31 extends downwardly therefrom, and engages in a cam-slot 38 in an enlarged portion 39 of locking lever 26; said enlarged portion having a shoulder 40 to engage a pin or projection 41, extending from the upper side of the line-space lever 9, to normally lock the line-space lever.

When the typist's finger is thrown against the finger-piece 42 of the top plate 31 to return the carriage to the right, the starting shock is taken up by the finger-piece.

Should the operator endeavor to operate the line-space handle 10 with an excessive force by moving the hand rapidly leftward towards said handle, the blow is broken by the pin 41, which bears against the shoulder 40 until the finger-piece 42 starts to move rightward, pin 37 operating in cam-slot 38 and thereby throwing the locking lever 26 rearward, which allows the pin 41 to move past the shoulder 40, and the line-space lever 9 to swing to the left until it comes into contact with the abutment 19. Before the line-space lever is released, the blow imparted thereto is broken, and the quick start of the platen and slip of the work-sheets are prevented.

The spring 16 returns the line-space lever 9 to its normal position simultaneously with the return of the top plate 31 to its normal position by the spring 34.

It should be understood that, with the use of a locking device for the line-space lever, the parts may be arranged as shown in Figure 5, in which parts similar to those shown in Figure 2 bear the same reference numerals with the exponent "a". It will be seen that the line-space handle or finger-piece 10 moves rightward and receives the impact of the hand while returning the carriage, as in the Underwood machine. The releasing

finger-piece 42^a is operable by the thumb, and moves leftward towards the line-space handle, to operate the locking lever 26^a, to release the line-space lever, prior to a line-spacing operation of the platen.

With this arrangement, the finger-piece 10^a is engaged by the forefinger of the left hand of the operator to return the carriage and operate the line-spacing mechanism, the locking device or lever 26^a being normally effective to prevent the impact of the hand of the operator from being transmitted to the platen; the finger-piece 42^a being near enough the line-space handle 10^a to be engaged by the thumb of the same hand to operate the locking lever 26^a and release the line-space handle. It will be understood that this form of my invention may readily be applied to the Underwood typewriting machine without materially altering the

Variations may be resorted to within the scope of the invention, and portions of the improvements may be used without others.

Having thus described my invention, I claim:

1. In a typewriting machine, the combination with a traveling carriage and a platen revolubly mounted therein, of line-space mechanism for said platen, a line-space lever to operate said line-space mechanism, means for locking said lever and normally preventing actuation thereof, and movable means for absorbing the shock of the hand in returning the carriage to the right, said movable means releasing said locking means when near the end of its movement to permit line-spacing of the platen.

2. In a typewriting machine, the combination with a traveling carriage and a platen revolubly mounted therein, of line-space mechanism for said platen, a movable finger-piece for absorbing the shock of the hand in returning the carriage to the right, a line-space lever mounted on the carriage for movement toward said finger-piece to operate said line-space mechanism, means for locking said lever and normally preventing actuation thereof, and means operable by the finger-piece for releasing said line-space lever from the locking means when near the end of the movement of the finger-piece to permit line-spacing of the platen.

3. In a typewriting machine, the combination with a traveling carriage and a platen revolubly mounted therein, of means for rotating the platen comprising a line-space lever, means normally rendering the line-space lever incapable of being operated to rotate the platen, a movable finger-piece on said carriage, adjacent to the lever, adapted to take the burden of moving the carriage when engaged by the typist's finger, and means operable by the finger-piece for rendering the line-space lever capable of being

operated by another finger to rotate the platen.

4. In a typewriting machine, the combination with a traveling carriage and a platen 5 revolubly mounted therein, of a line-space lever to cause rotation of said platen, a movable finger-piece, adjacent said lever, for moving the carriage, and means associated with said finger-piece for causing the lever 10 to be held in fixed relation to the finger-piece until the latter is moved by the typist's finger to start the carriage.

5. In a typewriting machine, a traveling carriage, a revoluble platen therein, line-spacing mechanism including a line-space lever, and means to absolutely prevent the operation of the line-space lever by a blow, whereby the likelihood of the paper slipping with reference to the platen during the 20 line-spacing operation is obviated.

6. In a typewriting machine, the combination with a traveling carriage and a platen revolubly mounted therein, of a line-space lever adapted to cause rotation of said 25 platen, means comprising a movable finger-piece on said carriage, adjacent said lever, adapted to take the burden of moving the carriage when the finger-piece is engaged by the typist's finger while another finger 30 operates said line-space lever, a locking member adapted to hold the line-space lever in its ineffective position, said locking member being controlled by the movement of said finger-piece, and means for retaining 35 the finger-piece in its normal position.

7. In a typewriting machine, the combination with a traveling carriage and a platen revolubly mounted therein, of a line-space lever adapted to cause rotation of said 40 platen, a follower fixed on the lever, a movable finger-piece adjacent said lever, a base plate extending between and having fixed relation with abutments on the front bar of the carriage, a locking lever underlying said 45 base plate, the locking lever having pivotal connection with one of said abutments and a pin-and-slot connection with said finger-piece, said connection serving to operate the locking lever during the movement of said 50 finger-piece, said locking lever adapted to engage said follower, and to cause the line-space lever to be held in fixed relation to said finger-piece when said finger-piece is in its normal position, means connected to said 55 base plate and co-acting with the finger-piece to urge the latter in one direction, means for limiting the movement of said finger-piece in either direction, and means for limiting the travel of the line-space lever 60 in either direction.

8. In a typewriting machine, the combination with a traveling carriage and a platen revolubly mounted therein, of line-spacing mechanism for said platen, a carriage-returning finger-piece upon the left-hand side 65

of the carriage, and a line-space lever mounted on the carriage to the right of the carriage-returning finger-piece for operative movement in an anti-carriage-return direction toward the carriage-returning finger-piece, the line-space lever being normally spaced to the right of the finger-piece a distance such as to enable the line-space lever to be engaged by the thumb of the left hand when the finger-piece is engaged by the index-finger of such hand, the arrangement being such that the operator may effect the line-spacing operation simultaneously with the return of the carriage but is compelled to effect it by a separately exerted force, thus obviating the slipping of the paper with reference to the platen, which is likely to occur where the line-spacing operation is effected by a carriage-returning blow.

9. In a typewriting machine, a traveling carriage, a revoluble platen therein, a carriage-return abutment for returning the carriage at the completion of each line, and line-spacing mechanism for rotating the platen, comprising a line-space lever, said lever being arranged to be operated in an anti-carriage-return direction, whereby the operator is compelled to effect the line-spacing operation by a separately exerted force from that which returns the carriage, thus obviating the slipping of the paper with reference to the platen, which is likely to occur where the line-spacing operation is effected by a carriage-returning blow.

10. In a typewriting machine, the combination with a traveling carriage and a platen revolubly mounted therein, of line-space mechanism for said platen, a line-space lever to operate said line-space mechanism, means for locking said lever and normally preventing actuation thereof, said means comprising a pivoted lever engaging said line-space lever, a movable finger-piece, the movement of said finger-piece serving to absorb the shock of the hand in returning the carriage to the right, and a connection between said finger-piece and pivoted lever whereby movement of the former displaces the latter, the final movement of said finger-piece serving to disengage said pivoted lever from said line-space lever to permit operation of the latter.

11. In a typewriting machine, the combination with a traveling carriage and a platen revolubly mounted therein, of line-space mechanism for said platen, a line-space lever to operate said line-space mechanism, means for locking said lever and normally preventing actuation thereof, said means comprising a pivoted lever engaging said line-space lever, and a movable finger-piece, the movement of said finger-piece serving to absorb the shock of the hand in returning the carriage to the right, said pivoted lever having a cam-slot, said finger-piece having a pin

engaging in said slot whereby movement of the finger-piece will displace said pivoted lever, the final movement of said finger-piece serving to disengage said pivoted lever from 5 said line-space lever to permit operation of the latter.

12. In a typewriting machine, the combination with a traveling carriage and a platen revolvably mounted therein, of line-space mechanism for said platen, a line-space lever mounted for pivotal movement on said carriage to operate said line-space mechanism, a slidably movable finger-piece mounted on said carriage for movement toward said 15 lever, said line-space lever and said finger-piece being spaced from each other lengthwise of the carriage, said finger-piece receiving the full impact of the hand in returning the carriage to the right, and locking means 20 controlled by said finger-piece for preventing movement of the line-space lever until near the end of the movement of the finger-piece toward said lever.

13. In a typewriting machine, the combination with a traveling carriage and a platen revolvably mounted therein, of line-spacing mechanism for said platen, a line-space lever mounted for operative and return movements on the carriage, connections between 30 the line-space lever and the line-spacing mechanism for advancing the platen upon each operative movement of the lever, means for normally locking said line-space lever to prevent actuation of the line-spacing 35 mechanism by a blow, and to thereby prevent actuation of said lever suddenly enough

to cause the paper to slip, a finger-piece movable towards said line-space lever, and means operable by the finger-piece when so moved to release the line-space lever from its 40 locking means, so that said lever may be operated by gripping the finger-piece and lever and pressing them toward each other to actuate the line-spacing mechanism.

14. In a typewriting machine, the combination of a traveling carriage and a platen revolvably mounted therein, line-spacing mechanism for said platen, a line-space lever to operate said line-spacing mechanism, a projection on said line-space lever, a pivoted 50 locking lever to engage said projection to hold said line-space lever against operation, and a slidably finger-piece, movable towards said line-space lever, to operate said locking lever to release said line-space lever. 55

15. In a typewriting machine, a traveling carriage, a revoluble platen therein, and line-spacing mechanism for the platen including a line-space lever, an abutment, said lever and abutment located to be gripped between 60 a thumb and finger of the operator, and means for compelling the operation of the line-space lever to be effected by opposed pressures upon the line-space lever and the abutment, and for thereby compelling the line-spacing operation to be effected slowly enough to obviate jerking the platen in a manner which would cause the paper to slip. 65
